CLAIM

The ornamental design for a pressure sensor, as shown and described.

DESCRIPTION

FIG. 1 is a top front perspective view of the pressure sensor; FIG. 2 is a bottom front perspective view of the pressure sensor of FIG. 1; FIG. 3 is a front view of the pressure sensor of FIG. 1, wherein the rear view is identical; FIG. 4 is a right side view of the pressure sensor of FIG. 1, wherein the left side view is identical; FIG. 5 is a top view of the pressure sensor of FIG. 1; and, FIG. 6 is a bottom view of the pressure sensor of FIG. 1. The shade lines on the surfaces of the pressure sensor show contour and not surface ornamentation.
